UNITED STATES PATENT OFFICE

JOHN LINDLEY THOMPSON, OF HAYES, ENGLAND

COOLING ARRANGEMENT FOR ELECTRICAL APPARATUS

Application filed July 15, 1929, Serial No. 378,459, and in Great Britain August 11, 1928.

This invention has reference to improvements in means for dissipating the heat generated in electrical apparatus of different kinds immersed in liquid within a casing, and particularly for dissipating the heat generated in an electric transformer contained within an oil filled tank.

For dissipating the heat generated in electrical apparatus immersed in liquid (hereinafter referred to as oil), contained within a casing or tank (hereinafter referred to as a tank), the top and bottom of the tank has usually been connected to a number of external vertically arranged air cooled tubular radiators, of various constructions, through which oil heated within the tank by the electrical apparatus, when the same is in use, is caused to flow by natural circulation, due to difference in the temperature of the oil at the top and bottom of the tank. Sometimes the tubular radiators have been traversed by tubes through which a cooling fluid, for instance water or air, is caused to flow, to increase the dissipation of heat from the oil, and in other cases the oil has been withdrawn from the upper part of the tank through a pipe by a circulating pump and passed through an external water cooled tubular cooling device from which it is returned through another pipe to the bottom of the tank.

Now the present invention has reference to a cooling arrangement suitable for use with oil cooled electrical apparatus, for instance an electrical transformer arranged within a tank filled with oil, and comprising external air or water cooled radiators connected to the top and bottom of the tank, whereby the oil can be caused to flow at a rapid rate through the radiators by a circulating pump and thence through the tank, so as to maintain it at a practically even temperature, or can be returned direct from the lower ends of the radiators to the bottom of the tank by natural circulation, as may be desired to suit the conditions of working of transformer.

For this purpose, the lower ends of the external radiators of the oil tank are connected by piping to the inlet of an oil circulating

pump and the outlet of such pump is connected to the bottom of the tank so that the oil can be forced to flow rapidly through the radiators and more slowly through the tank and in contact with the transformer or other electrical apparatus (hereinafter referred to as the transformer) therein so as to maintain the oil at a nearly uniform temperature throughout the circulating system, as when the transformer is working at or near full load, and each radiator is also connected to the lower end of the tank through a valve controlled pipe that is closed when the pump is in operation and is opened when the transformer is working at a low or lower load, so that the natural circulation of the oil through the radiators and tank can then take place and the pump be put out of operation so as to avoid the cost of running it at this time. The valves controlling the direct communication between the lower ends of the radiators and the bottom of the tank may advantageously be non-return valves adapted to close automatically when the pump is put in operation and to open inwardly in an automatic manner when the pump is stopped.

In the accompanying illustrative drawings, Fig. 1 shows in elevation and Fig. 2 in plan one construction of oil cooling means according to the invention applied to a transformer tank, provided with air cooled radiators. Fig. 3 is a detail view. Figs. 4 and 5 are similar views to Figs. 1 and 2 showing a modified arrangement. Figs. 6 and 7 show diagrammatically other modified arrangements. Fig. 8 shows the invention applied to a transformer provided with water cooled radiators.

Referring to the example shown in Figs. 1 and 2 of the drawings, the external vertical air cooled radiators 1 arranged around the transformer tank 2, are connected at their upper ends or headers 1^a by valve controlled junction pipes 3 to the upper part of the tank so that warm oil can enter them from the tank, and at their lower ends are connected by vertical pipes 4 to a lower horizontal pipe 5, that extends around the tank 2, is of larger cross sectional area than each of the vertical pipes 4 and is connected at different points in its length to suction pipes 6 connected to the

suction side of oil circulating pumps 7, with a view to obtaining a practically uniform flow of oil through all the radiators, the delivery side of the pumps being connected by other pipes 8 to different points of the lower end of the tank 2. The lower ends, or headers 1^b of the radiators 1 are also connected direct to the bottom of the tank through horizontal pipes 9 provided with controlling valves 10 and are preferably inwardly opening sensitive non-return valves for the reason hereinbefore mentioned. A valve of this kind is shown in Fig. 3 in section and to a larger scale than Figs. 1 and 2. It comprises a flap valve 10 mounted in a casing 10^a to open inwardly, so that when the pumps 7 are working it will be closed against its seat 10^b by the sucking action of the pump, but will be opened automatically by the pressure of the oil descending in the radiator, caused by natural circulation, when the pumps are stopped. A flap 11 may, as shown, be suspended in the oil passage 10^c by a flexible diaphragm 11^a and be provided with an external pointer 11^b arranged 25 to work over an indicator face 11^c whereby it can be ascertained whether the valve 10 is open or closed. The valve 10, in the example shown, is carried by a link 10^d pivoted at 10^e and provided with an arm 10^f whereby the 30 valve can be held closed by a locking screw 10^g when this may be desired, as for instance, when it is desired to disconnect the radiator from the tank. Hand controlled valves could of course be used instead of the automatic 35 valves but obviously not so advantageously.

Instead of connecting the lower end of each radiator 1 to the bottom of the tank by a valve controlled pipe 9, as hereinbefore described, the horizontal pipe 5 to which the radiators 40 are connected, may, as shown in Figs. 4 and 5, be connected at a number of points in its length to the lower portion of the tank through pipes 9^a provided with controlling valves 10 for the purpose set forth. In this 45 example, the valves 10 are shown as hand operated sluice valves. In this example also, the header 1^a at the upper end of each radiator 1 is connected laterally to the upper end of the tank 2 by a valve controlled T-shaped pipe 3 to which another radiator can be connected, as shown at 1^c so that one pipe 3 can be common to two radiators. Also, the headers 1^b at the lower end of the radiators 1 are connected laterally to valve controlled 50 T-shaped pipes 9^a, the several pipes 9^a being connected through the said lower headers 1^b to the suction pipe 6 connected to the pumps 7.

Each pump 7 may, as shown in Figs. 1 and 2, be arranged to be driven by a pulley 7^a and 60 belt from an electric or other motor, not shown, or, as shown in Figs. 4 and 5, each pump may be arranged to be driven direct by an electric motor 12.

If desired or required, a tubular water cooled device 13 may, as indicated in Fig. 6, be

connected in a shunt conduit to an oil delivery pipe 8 of each circulating pump 7 so that by closing a valve 14 in the said pipe between its points of connection to the tubular water cooled device 13, the oil, after leaving the pump, can be caused to flow through such cooling device on its way to the bottom of the tank.

Fig. 7 shows, diagrammatically, how the lower ends of radiators 1 connected by valve controlled pipes 9 can be connected by the suction pipes 6 to a single pump 7 connected by delivery pipes 8 to the bottom of the tank 2.

The radiators may, as hereinbefore stated, be water cooled radiators. One such radiator is shown at 15 in Fig. 8, 15^a being the water inlet and 15^b the water outlet. The lower end portions of such radiators are connected laterally through pipes to the oil circulating pump or pumps as in the other arrangements hereinbefore described.

The cooling arrangements hereinbefore described are specially suitable for use with an oil cooled transformer having a self cooled rating and a forced cooled rating.

By the use of cooling arrangements such as hereinbefore described, a more efficient use of the radiating surfaces available can be obtained, and the flow of oil in the cooled radiator units can be more equally distributed than is usual with forced cooled units, thus ensuring more uniform temperature throughout the transformer or other electrical apparatus enclosed in the tank. Consequently, by using such cooling arrangements with standard naturally cooled transformers or units, large overload capacities are available. Furthermore, the cooling effect can be made automatic, thus eliminating the human element.

What I claim is:—

1. A cooling arrangement suitable for use with liquid cooled electrical apparatus, comprising, in combination with a tank for the electrical apparatus, external radiators each connected at its upper end to the upper part of said tank, an oil circulating pump to which the lower ends of said radiators are connected and which is in communication at its delivery side with said tank, and a valve controlled connection between the lower end of each radiator and the lower end of said tank, said connections being capable of being closed when said pump is in operation and of being opened when said electrical apparatus is working at a low load and the pump is out of operation.

2. A cooling arrangement suitable for use with liquid cooled electrical apparatus comprising, in combination with a tank for the electrical apparatus, external radiators each connected at its upper end to the upper part of said tank, an oil circulating pump to which the lower ends of said radiators are connected and which is in communication at its delivery side with said tank, and a valve con-

- trolled connection between the lower end of each radiator and the lower end of said tank, the valve controlling each of said connections being a non-return valve adapted to close 5 automatically when said pump is put in operation and to open inwardly in an automatic manner when said pump is stopped.
3. A cooling arrangement according to claim 1, having a secondary cooling device 10 connected in shunt to the liquid delivery pipe of said circulating pump and valve means whereby said secondary cooling device can be put in and out of use at will, for the purpose described.
- 15 4. A cooling arrangement suitable for use with liquid cooled electrical apparatus, comprising, in combination with a tank for the electrical apparatus, external radiators each connected at its upper end to the upper part 20 of said tank, a pipe extending around said tank, tubular connections between the lower ends of said radiators and said pipe, an oil circulating pump the suction of which is in communication with said pipe and the delivery side of which is in communication 25 with the lower end of said tank, tubular connections between the lower ends of said radiators and the lower end of said tank and controlling valves in said last mentioned tubular connections.
5. A cooling arrangement suitable for use with liquid cooled electrical apparatus, comprising, in combination with a tank for the electrical apparatus, external radiators each 30 connected at its upper end to the upper part of said tank, a pipe extending around said tank, tubular connections between the lower ends of said radiators and said pipe, an oil circulating pump the suction side of which 35 is in communication with said pipe and the delivery side of which is in communication with the lower end of said tank, tubular connections between the lower ends of said radiators and the lower end of said tank, and inwardly opening non-return valves in said 40 last mentioned tubular connections.
6. A cooling arrangement for cooling liquid in a tank, comprising, in combination with the tank, external radiators connected 45 at their upper and lower ends to the upper and lower end portions of the tank, valves for controlling the communication between the lower ends of the radiators and the tank, a liquid circulating pipe common to said 50 radiators, tubular connections between the lower ends of said radiators and circulating pipe, and a plurality of pumps connected on their suction side to said pipe and on their delivery side to the lower portion of said 55 tank.
7. A cooling arrangement for cooling liquid in a tank, comprising, in combination with the tank, external radiators connected at their upper and lower ends to the upper 60 and lower end portions of the tank, auto- 65 matic inwardly opening non-return valves between the lower ends of said radiators and tank, a liquid circulating pipe common to said radiators, tubular connections between the lower ends of said radiators and circulating pipe, and a plurality of pumps connected on their suction side to said pipe and on their delivery side to the lower portion of said tank.
8. A cooling arrangement for cooling liquid in a tank, comprising, in combination with the tank, external radiators connected at their upper and lower ends to the upper and lower end portions of a tank, automatic inwardly opening non-return valves between the lower ends of said radiators and tank, means adapted automatically to indicate the open or closed position of said non-return valves, a liquid circulating pipe common to said radiators, tubular connections between the lower ends of said radiators and circulating pipe, and a plurality of pumps connected on their suction side to said pipe and on their delivery side to the lower portion of said tank.

Signed at London, England, this fifth day 90
of July, 1929.

JOHN LINDLEY THOMPSON.
